UNITED STATES PATENT OFFICE.

ELISHA L. WILLIAMS, OF LITTLE ROCK, ARKANSAS.

MACHINE FOR APPLYING SPOKE-PROTECTORS.

1,083,171.

Specification of Letters Patent. Patented Dec. 30, 1913.

Application filed April 18, 1913. Serial No. 762,014.

To all whom it may concern:

Be it known that I, ELISHA L. WILLIAMS,
a citizen of the United States, residing at
Little Rock, in the county of Pulaski and
5 State of Arkansas, have invented new and
useful Improvements in Machines for Ap-
plying Spoke-Protectors, of which the fol-
lowing is a specification.

This invention relates to machines for applying spoke protectors and like devices and the object of the invention is the provision of a simple and efficient structure which will permit all of the protectors to be simultaneously forced into position between the spokes and held while the rivets or retaining members are placed therethrough and through the retaining bands usually employed.

A further object of the invention is to provide a machine of this character in which an even pressure may be obtained for all of the spoke protectors so that unequal pressure will not be produced upon any of the spokes.

25 Further objects of the invention will appear as the following description is read in connection with the accompanying drawings, which form a part of this application, and in which:—

30 Figure 1 is an elevation of the machine. Fig. 2 is a vertical sectional view showing the hub in place. Fig. 3 is a horizontal section taken on the line 3—3 of Fig. 2. Fig. 35 4 is a detail horizontal section through one of the clamping heads. Fig. 5 is a detail section through the wheel showing the arrangement of the protectors therein. Fig. 6 is a detail perspective view showing one of the spoke protectors with the retaining 40 flanges on opposite sides thereof in section.

Referring more particularly to the drawing, 1 represents a standard which is supported upon diverging legs 2 and is provided with a central bore 3 through which the operating shaft or rod 4 is adapted to pass. The upper end of the standard has mounted thereon an anvil 5 upon which the hub 6 is adapted to rest and the bore 3 is so arranged as to register with the anvil bore 7 and the axle opening in the hub. Secured to the top of the standard between the same and the anvil 5 is a cup-shaped pivoting member 8 having an enlarged rim 9 upon which are pivoted the rock levers 10 having pivotal connection at their lower ends with the links 11 of what may be termed a plurality of

toggle levers coupled together in their centers by a cup-shaped member 12 similar to that shown at 8 and also provided with an enlarged rim 13 for engagement with the notches 14 in the inner ends of the links 11. 60

The upper ends of the rock levers are threaded so as to receive the threaded shanks 15 of the clamping heads 16. These clamping heads are adapted to be brought into engagement with the spoke protectors 17 which are wedge-shaped in cross section and conform to the outline of the spokes, as shown in Fig. 6. These spoke protectors are apertured as shown to receive the clamping rivets 19 which connect them to the retaining rims 20 arranged on the opposite side of the spokes in the wheel. 85 70

The upper end of the rod 4 is provided with screw threads 21 to receive the operating lever 22 which when operated bears against the hub 6 and draws the rod 3 through the standard, raising the cup-shaped member 12 and spreading the toggle levers 11 which contracts the upper ends of the rock levers and presses the clamping heads into engagement with the spoke protectors so that the apertures of the latter will be brought into register with the apertures in the retaining rings while the rivets are being placed in position. 75 80 85

It will be noticed that both the rock levers and the links 11 are removably engaged with their cup-shaped members 8 and 12 so that the machine may be readily adjusted for operating on the wheels having a large or small number of spokes. 90

What I claim is:—

What I claim is:—

1. A machine of the character described comprising a standard, an anvil carried thereby and adapted to support a hub, a pivoting member carried by the standard, pressure members mounted upon the pivoting member for forcing protector members between the spokes of the hub and operating means for the pressure members which has a part passing through the standard and hub. 95 100

2. A machine of the character described comprising a standard, an anvil mounted upon the standard and adapted to support a wheel hub, a pivoting member carried by the standard, pressure members removably connected to the pivoting member for pressing protector members between the spokes of the hub and means for operating said pressure members, said operating means

having a part passing through the standard and hub and a part adapted to hold the hub on the anvil.

3. A machine of the character described comprising a standard adapted to support a hub and having a central bore therethrough to register with the bore in the hub, rock levers removably pivoted to the standard and having adjustable pressure members carried by one end thereof, toggle links pivoted to the opposite ends of the rock levers, means for connecting the inner ends of the toggle links, an operating rod pass-

ing through the central bore in the hub and connected to the connecting means and a lever threaded upon the upper end of the rod and adapted to bear against the hub for holding said hub against the anvil and for lifting the connecting means to straighten the toggle levers. 20

In testimony whereof I affix my signature in presence of two witnesses.

ELISHA L. WILLIAMS.
